Primary Examiner—James Gandy*Assistant Examiner*—Linda Brooks[57] **CLAIM**

The ornamental design for a picnic table bench cover, as shown and described.

DESCRIPTION

FIG. 1 is a front elevational view of the picnic table bench cover showing our new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

FIG. 7 is a side view thereof with the straps fastened securely under the bench portion, with a picnic bench shown in broken lines for purposes of illustration only and forming no part of the claimed design, it being understood that the opposite side is a mirror image.

The pattern of criss-cross lines shown partially on the surface of the picnic table bench cover in FIGS. 1-7 is understood to repeat uniformly across the entire surface.
